UNITED STATES PATENT OFFICE

EDWARD O. VANDERCOOK, DAVID D. VANDERCOOK, AND FREDERICK R. VANDERCOOK, OF EVANSTON, ILLINOIS, ASSIGNEES TO VANDERCOOK AND SONS, OF CHICAGO, ILLINOIS, A COPARTNERSHIP COMPOSED OF ROBERT O., EDWARD O., DAVID D., AND FREDERICK R. VANDERCOOK

AUTOMATIC CYLINDER TRIP FOR PRINTING PRESSES

Application filed June 1, 1931. Serial No. 541,209.

Our invention relates to improved cylinder trip mechanism particularly useful in connection with proof presses for automatically raising the printing cylinder to clear it from the type or other set up during the return of its supporting carriage after a printing operation.

An important object of the invention is to provide a single means in the form of a cam bar for cooperating with the cylinder bearing frames to raise or lower said frames at the proper time.

Another important object is to provide improved and simplified tripping means for controlling the shift of the cam bar at the proper time and thereby the elevation of the printing cylinder.

Still another object is to provide additional tripping means for allowing shorter travel of the cylinder carriage when shorter sheets are to be printed, thereby saving time and labor.

The above referred to features and other features of our invention are incorporated in the structure disclosed on the drawings, in which drawings

Figure 1 is a front elevation of a proof press to which our invention is applied;

Figure 2 is a rear elevation of the press;

Figure 3 is a section on plane III—III of Figure 2;

Figure 4 is a section on plane IV—IV of Figure 3; and

Figure 5 is a plan view of a side section of the machine showing the arrangement of the tripping element and the cooperation of the cam bar therewith.

The press structure shown comprises a rectangular bed frame 1 having on each side a track flange 2 and above it a gear rack 3. The cylinder supporting carriage comprises the side frames 4 and 5 connected by cross rods 6, each side frame journalling a set of wheels 7 engaging the respective rail flange 2.

The printing cylinder 8 is mounted on a shaft 9 which is journalled at its ends in bearing frames 10 and 10', these bearing frames being pivoted or hinged at their left ends to the carriage frames 4 and 5 respectively as indicated at 11 and 11', the bearing

frames at their right ends being supported by a cam bar 12 which will be referred to more in detail hereinafter.

A gear 13 is secured to each end of the printing cylinder and meshes with the corresponding rack 3 so that when the cylinder is turned by means of the crank handle 4 on the front end of its supporting shaft, the gears will travel along the racks to propel the cylinder carriage along the machine bed frame in a manner well understood in the art.

A cross bar 15 meshing between the left ends of the carriage frames 4 and 5 supports a feed apron or board 16 on which sheets to be printed are fed into proper position relative to the printing cylinder. Brackets 17 and 17' on the right ends of the carriage frames support side bars 18 and 18' which serve to support the framework for the inking rolls, one of such rolls 19, being diagrammatically indicated, it being understood that a suitable inking plate is provided for the rolls which rolls are carried across the type or other set up to apply ink thereto during the operation of the machine.

The tripper or cam bar 12 is preferably of steel and of rectangular cross section. It extends transversely across the machine and is guided at its ends in the rectangular openings 20 and 21' provided in the carriage frames 4 and 5 respectively. The sections of the frames 4 and 5 above the guide passageways may be in the form of removable plates 21 and 21' for facilitating removal of the cam bar.

As best shown in Figures 3 and 4 each of the cylinder journalling frames 10 and 10' has its right upper corner cut away to leave a rectangular recess providing a horizontal cam surface 22 and a vertical wall 23. The cam bar 12 engages at its underside with the cam surface 22 and above the cam surface each frame has a cam roller 24 journalled adjacent to the vertical surface 23 by a suitable pin 25, these cam rollers engaging with the upper side of the cam bar 12. In its upper side the cam bar has the depressions or notches 26 for receiving the rollers 24 and in its underside and to the right of the notches 100

- 26 the cam bar has the depressions or notches 27, these notches being adapted to receive the ends 28 of the frames 10 and 10' for engagement of the cam surfaces 22 with the bar. 5 The relative location of the depressions 26 and 27 is such that when the bar is in one position as shown in Figure 3 the cam rollers will be in the notches 26 and the cam surfaces 22 will be in engagement with the straight 10 underside of the cam bar, and when the bar is shifted to the left from the position shown in Figure 3 the cam rollers will engage with the top side of the cam bar and the ends 28 of the frames 10 and 10' will be in the notches 15 27, longitudinal shift of the cam bar thus elevating and lowering the right ends of the frames 10 and 11 to swing such frames around the pivotal supports 11 and 11' and thereby elevate the printing cylinder above 20 the type or other set up on the press bed or to lower the cylinder for printing cooperation with the type or other set up to be printed.

Describing now the means for shifting the 25 cam bar 12, the cam bar at its rear end has a link 29 pivoted thereto which extends inwardly thereof and is pivoted at its inner end to an arm 30 extending from the upper end of a vertical shaft 31 which is journalled 30 on the carriage frame 5 as clearly shown in Figure 2. At its lower end the shaft has the arm 32 extending therefrom in a direction opposite to that of the arm 30, and at its end the arm 32 journals a roller 33 for cooperation 35 with the tripping or switch structures located in the path thereof.

We have shown the end tripping or switch structures A and B, and in accordance with our invention we provide an additional or intermediate switch structure C for cooperating 40 with the roller 33 to swing the arm 32 and rotate shaft 31 for shifting of the cam bar 12.

The switch structure A is located at the ink plate end of the press bed and the switch 45 structure B is located at the other end, the switch structure C being between the two. The switch structure A comprises a supporting plate or bracket 34 secured to and extending horizontally from the press bed 50 frame and at its outer end has the vertical projection 35 forming the guide surface 36 which inclines from its inner end towards the press bed frame. A switch tongue 37 is 55 pivoted at its inner end on the bracket 34 as indicated at 38 and extends toward the guide projection 35. A suitable spring structure 39 engages the switch tongue and tends to hold it in an outer position indicated in 60 Figure 5 to leave a passageway between the switch tongue and the press bed frame for travel of the roller 33.

The switch structure B comprises a supporting bracket 40 on which a switch tongue 65 41 is pivoted to extend laterally in a direc-

tion opposite to that of the switch tongue 37, a suitable spring 42 tending to hold the switch tongue 41 in inclined position with its ends against the press bed frame.

The intermediate switch structure C is constructed and arranged the same as the structure B and comprises a supporting bracket 43, the switch tongue 44, and the spring 45. When a full size sheet is to be printed the printing cylinder carriage will be shifted for cooperation of the roller 33 with the switch structure A and with the end switch structure B. For smaller size sheets the carriage need be shifted only for cooperation of the roller 33 with the intermediate switch structure C. Therefore for smaller sizes of forms to be printed the printing cylinder need not be given the full travel and considerable time and labor will be saved.

Describing now the operation, Figure 1 shows the carriage at the right end of its travel ready for printing movement toward the left, and Figure 2 shows the carriage at the other end of its travel after a printing operation. When the carriage was travelling to the right (Figure 1) the roller 33 was shifted inwardly by the switch mechanism A thereby swinging the arm 32, rotating the shaft 31, and swinging the arm 30 to cause the cam bar 12 to be shifted to the rear to the position shown in Figure 3 to cause the frames 10 and 10' to be swung down to bring the printing cylinder into printing position. The operator now feeds a sheet along the feed board 16 and by means of the crank handle 14 he rotates the cylinder and the carriage is shifted to the left while the cylinder impresses the sheet against the type or set up on the press bed. As the carriage travels to the left (Figure 1) the roller 33 engages against the rear side of the switch tongue 44 of the intermediate switch structure C and swings this tongue outwardly against the pull of its spring 45, and after the roller passes the switch point the switch tongue is returned to closed position by the spring 45 and if there is a short form or sheet in the press the operator will then reverse the crank 14 to shift the carriage in the opposite direction and during such reverse travel the roller will travel along the outer inclined side of the switch tongue 44 and the shaft 31 will be rotated to cause the cam bar 12 to be shifted forwardly so that the cam rollers 24 will come into engagement with the top side of the cam bar and the frames 10 and 10' will be swung upwardly to raise the printing cylinder to clear the type or set up on the press so as not to smudge the ink which has been deposited on the type by the inking roll following the printing operation. The cylinder will remain in elevated position until the roller 33 has traveled through the end switch structure A. As the roller enters this switch structure outside

of the switch tongue 37 it encounters the inclined surface 36 and is deflected inwardly to swing the arm 32 and rotate the shaft 31 to shift the cam bar 12 to its rear position 5 (Figure 3) so that the printing cylinder is lowered to its printing position and then as the carriage is again shifted toward the left (Figure 1) the cylinder will remain down during the printing operation and until it 10 has passed the intermediate switch mechanism C or the end switch mechanism B and then upon reverse travel of the carriage the roller 33 is again deflected outwardly and the cam bar 12 shifted to cause elevation 15 of the printing cylinder. When full size sheets are being printed the carriage is moved the entire distance for cooperation with the end switch structure B but, as before explained, for shorter sheets the carriage need 20 be shifted only past the switch structure C. The click of the release switch tongue 44 against the press bed by its spring 45 will notify the operator when the switch mechanism C has been passed.

25 The switch structure A at the ink plate end of the press bed may be permanently secured in place as the carriage must always be shifted the full distance to the ink plate end of the press. The other end switch B 30 may be permanently secured in position and the intermediate switch C may be adapted to be adjustably secured to the press bed frame so that adjustment can be made corresponding to the size of the forms or sheets 35 to be printed. It is evident that instead of the two switch structures C and B only one could be used and made adjustable so as to be located for full travel of the carriage or for shorter travel.

40 To facilitate the operation of the press a table structure 46 may be mounted on the carriage for supporting the stack of sheets to be printed. A plate or board 47 may also be provided to form an extension to the 45 feed board 16 to facilitate feeding of sheets to the printing cylinder, and the board 47 may have an extension 48 forming a support on which the printed sheets may be deposited and stacked.

50 The cylinder elevating or tripping means comprising the single cam bar 12 simplifies the construction and operation and assures simultaneous and uniform movement of the frames 10 and 10' to elevate or lower the 55 printing cylinder supported thereby and the cylinder will be held accurately in the proper position for uniform impression of sheets against the printing forms. By means of the cam engagement of the cam bar with the 60 cylinder supporting frame very little power is required to shift the cam bar. Furthermore by having the single cam bar only a single set of switch elements is necessary.

We have shown a practical and efficient 65 embodiment of the various features of our

invention but we do not desire to be limited to the exact details shown and described as changes and modifications may be made without departing from the scope and principles of the invention as defined in the appended claims. 70

We claim as follows:

1. In a printing press, the combination of the press bed, a printing carriage reciprocable thereon, a printing cylinder and supports on said carriage therefor, a cam bar extending transversely on said carriage and guided thereby, cam connections between said bar and said cylinder supports adapted upon longitudinal shift of said bar to raise or lower 80 said supports and the cylinder supported thereby, and means controlling the shifting of said cam bar. 75

2. In a printing press, a printing carriage, a printing cylinder, bearing frames for said cylinder supported on said carriage, a cam bar extending transversely of said carriage and having cam engagement with said bearing frames to move said frames vertically when said bar is shifted longitudinally, and 90 means controlling the operation of said bar. 85

3. In a printing press, the combination of the printing bed, a carriage, a printing cylinder, adjustable bearing frames on said carriage for the ends of said cylinder, a cam bar shiftable transversely on said carriage, cam abutments on said bearing frames engageable by said cam bar to move said frames to raise or lower said cylinder relative to the press bed, and means for automatically controlling the shift of said cam bar. 95 100

4. In a machine of the class described, a printing bed, a carriage movable thereon, a printing cylinder, bearing frames for the ends of said cylinder movably supported on said carriage, cam abutments on said bearing frames, a cam bar parallel with the cylinder axis and guided by said carriage for reciprocation thereon for engagement with said cam abutments to move said bearings to adjust 105 said cylinder relative to the press bed, an actuating train on said carriage connected with said cam bar, and actuating means on the press bed in the path of said actuating train for causing operation of said train to 110 shift said cam bar. 115

5. In a machine of the class described, the combination of a press bed, a carriage for travelling thereon, a printing cylinder, movable supports on said carriage for the cylinder ends having cam abutments, a single cam bar shiftable on said carriage for cooperation with said cam abutments to move said supports to raise or lower said cylinder relative 120 to the press bed, and cooperating means on said carriage and said press bed operable during travel of the carriage to control the shifting of said cam bar. 125

6. In a machine of the class described, the combination of a press bed, a carriage mov- 130

- able thereon and having side frames, a printing cylinder between said side frames having a supporting shaft, bearing frames for the ends of said shaft pivoted to said side frames and having cam abutments, a single cam bar extending between and guided by said side frames to be shifted longitudinally for cooperation with said cam abutments to rock said bearing frames for elevating or lowering the cylinder relative to the press bed, a vertical shaft journalled on said carriage, a connection between said shaft and cam bar adapted upon rotation of said shaft to shift said cam bar, an arm on said shaft having a guide extension, and guide members on said press bed for guiding said guide extension to cause swing of said arm and rotation of said shaft whereby to cause shift of said cam bar and adjustment of said cylinder.
7. In a printing press, the combination of a press bed, a carriage thereon, a printing cylinder having a supporting shaft, vertically movable bearing frames on said carriage for the ends of said shaft, cam abutments on said bearing frames, a single cam bar shiftable on said carriage parallel with the cylinder axis for cooperating with said cam projections to move said bearing frames to adjust said cylinder relative to the press bed, transmission mechanism on said carriage connected at one end with said bar, and means on said press body in the path of the travelling carriage for cooperating with the other end of said transmission mechanism to cause operation thereof to shift said cam bar.
8. In a machine of the class described, the combination of a press bed, a carriage for travelling thereon, a printing cylinder, movable supports on said carriage for said printing cylinder, cam projections on said supports, a cam bar extending parallel with said cylinder and supported by said carriage to be shifted for cooperation with said cam projections to cause raising or lowering of said cylinder relative to the press bed, motion transmitting mechanism on said carriage connected with said bar, means on the press body at the ends of the carriage travel for cooperating with said motion transmitting means to cause operation thereof to shift said cam bar, and intermediate means on the press body for cooperating with said motion transmitting means for shift of said cam bar.

In testimony whereof, we have hereunto
55 subscribed our names at Chicago, Cook
County, Illinois.
